DES. 2082

Fish Mills, of Washington, Dist. of Columbia

Letters Patent No. 3482-Dated June 6-1865

Design for a Bust of Abraham Lincoln.

The schedule referred to in these Letters Patent and making part of the same.

Wall whom it may concern:

Be it known that G. Fish Mills, of the City of Washington, and District of Columbia, have originated and produced a new Bust of the late President Abraham Lincoln, of which the following is full, clear and exact description, reference being had to the accompanying photographs making part of this specification.

This Bust is modeled from a cast taken from the living face in the month of Feb. 1865, by Clark Mills process, and bears the following inscription modeled from a cast taken from the living face Feb. 14th 1865 and differs from all other like pieces in being a perfect facsimile of the face, physiognomical and phrenologically, bearing the callipers being applicable to the cast for minute exactness of features and organs. Other busts being modeled by looking at the person, lose this exactness, as the callipers are not minutely applicable to the living face, and the fidelity wholly cut adrift to the accuracy of the eye.

What I claim as my production and device secure by Letters Patent is, The design for the head and neck of the bust herein set forth.
